ROOFING

Harry L. Guy, Chicago, Ill., assignor to Ford Roofing Products Company, Chicago, Ill., a corporation of Illinois

Application December 17, 1931, Serial No. 581,565

6 Claims. (Cl. 108—33)

This invention relates to roof coverings and among other objects aims to provide roofing capable of covering larger areas of roof surface without impairing the protection against leakage.

5 The nature of the invention may be readily understood by reference to illustrative embodiments thereof shown in the accompanying drawing.

In said drawing:

10 Fig. 1 is a perspective view of a roof covering presenting hexagonal shingle outlines;

Fig. 2 is a roof covering formed from square individual shingles arranged in so-called diamond pattern;

15 Fig. 3 is a roof covering in which the shingles present the conventional square-butt outline;

Fig. 4 is a roof covering formed by overlapped courses of rectangular shingles arranged in a so-called Dutch lap relationship; and

20 Fig. 5 is an enlarged section taken on the plane 5—5 of Fig. 1 showing the manner of fastening down the free ends of the overlying shingle tabs. To simplify illustration the ends of the fastener are shown separating the lower layers of material, whereas in practice the fastener becomes embedded in the soft material of the roofing units.

The invention is here shown embodied in roofing material made from flexible asphalt-coated 30 roofing sheets which are usually surfaced with some colored mineral surfacing, such as a crushed slate. Such roofing material is cut into individual shingles or into so-called shingle strips having a plurality of shingle tabs which, when 35 laid in overlapped courses, simulate individual shingle outlines. It is desirable from the standpoint of appearance as well as of economy, to have the exposed areas of the shingles or shingle tabs as large as possible. Among other reasons 40 this is because the more expensive rigid roofing units, such as slate etc., can be and are laid with large areas exposed (relative to the unexposed area), thereby producing a more attractive appearance.

45 It has not been possible heretofore to simulate this large-shingle effect or to utilize the possible economies inherent therein, without providing some locking or a fastening means to hold down the free edges of the shingles or shingle tabs to 50 prevent their being blown up by wind to admit rain and cause leakage. Locking means whether in the form of a so-called lock shingle or otherwise not only affects the appearance or shape of the shingle or distorts the outline into some unattractive, unconventional shape which betrays the locked, flexible shingle, but results in buckling the roofing or producing bulges or wrinkles which prevent the roofing from lying flat. This effect is magnified in the heavier grades of roofing material and has therefore practically eliminated its

use from this type of shingle notwithstanding its obvious advantages.

Whatever form of lock shingle or locking means is employed, the desired effect is completely lost and no satisfactory large-shingle roof surface has been possible either in simulation of the effects produced by the more expensive rigid shingle or otherwise.

According to the present invention flexible shingles or strips having conventional large-shingle outlines may be fastened down by means which leave the roofing intact as regards leakage, which involve no alteration of the shingle outline, and which cause the shingles to lie flat without buckles or wrinkles. The invention has been 10 illustrated in the drawing in connection with a number of conventional shingle outlines. In Fig. 1 the roof surface is produced by so-called hexagon strips 10 (each having a plurality of spaced 15 projecting semi-hexagonal tabs 11) laid in overlapping courses with the ends 12 of the shingle tabs of one course registering with the bases 13 of the recesses between the shingle tabs of the next underlying course. The result produced is 20 a hexagonal shingle outline which of course may be considerably varied not only as to size but as to proportions of the sides of the shingle outline. As herein shown the depth of each shingle strip 10 is made great enough so that the upper 25 edge 14 of a given course underlaps by the distance 15 (which is usually about 2 or 2½") the bases 13 of the second overlying course of strips. Thus at the ends 12 of each of the tabs 11 and 30 for a distance 15 above the same, three thicknesses 16, 17 and 18 of roofing material occur 35 (see Fig. 5). The strips are here shown nailed as at 19 by nails or the equivalent which underlie the tabs 11 but pass through the subjacent layers 17 and 18 of the roofing. The heads of the 40 nails or other appropriate fastening means are therefore concealed and protected. The free ends 12 of the shingle tabs are fastened down in the region of the nails by fasteners 20, here shown in the form of metal clips similar to the wire or flat "Hotchkiss" fasteners, which penetrate 45 the upper two thicknesses 16 and 17 of the roofing but are independent of and do not penetrate the underlying thickness 18. Thus the free edges of the shingle tabs are fastened down in a manner 50 which permits them to lie perfectly flat and without penetrating the bottom layer of roofing material, thus leaving the latter imperforate to protect against leakage at this point. Moreover the fastener is independent of the lower layer of 55 roofing material and the attaching nails and their location. It is possible therefore to locate the attaching nails without regard to the fasteners. Where there are spaced roof boards the nail can- 60 not always be placed in a definite place on the

shingle but must be located where it can strike shingles are each clipped as at 30 and abut instead of overlap, to avoid an excessive number of thicknesses of roofing at each corner. In the present arrangement at each corner occur three thicknesses of roofing material the lowermost of which is the upper corner 31 of a shingle 27, the intermediate layer being the overlying margins 32 of the next course above, and the top layer being the lower corner 33 of the next higher course of shingles. The fastening nails 34 lie under the lower corners 33 of a course of shingles and penetrate the two subjacent layers. The fasteners 20 penetrate the upper two thicknesses of material at the corner and overlie the bottom thickness comprising the upper corners 31 of the course of shingles. The fasteners 20 may be applied after each course of roofing has been laid, in the manner illustrated in connection with Fig. 1, that is, by inserting the extremity 24 of plate 22 underneath the upper two layers of material at the lower corner of the given shingle but above the bottom thickness. Thus the free lower ends 33 of each shingle are fastened to the next underlying layer of material comprising the margins 32 which in turn are held down by the closely adjacent fastening nails 34, but the lower layer is not penetrated by the fastener 20 and no opportunity for leakage is afforded.

At the abutting vertical joints between adjacent strips or shingles, the fastener 20 is preferably placed, as shown in Fig. 1, to straddle the joint. The fasteners may advantageously be applied by typical fastener applying devices commonly found on the market. Such a device is indicated diagrammatically at 21 and comprises a fastener magazine which holds a supply of fasteners and a plate 22 hinged at 23 to the rear edge of the device and having its extremity 24 arranged opposite the point of application of the fastener to serve as a die in bending the ends of the fastener after they have penetrated the roofing. The plate 22 is preferably made narrow so that it may readily pass into the narrow space between adjacent square-butt shingles and should preferably be thin to avoid distorting the shingles upon application of the fasteners. The extremity 24 of the plate may if necessary be somewhat wider than the shank of the plate so as to be engaged by and bend over the extremities of the fastener. The device 21 may advantageously be of a type which is spring-operated and is actuated merely by depressing the trigger or handle 25. In order to fasten the shingle tabs as aforesaid it is necessary merely to insert the end 24 of the plate underneath the overlying thicknesses of material but above the bottom thickness and depress the trigger. If desired the body of the device may be equipped with an adjustable gauge 26 to engage the edge of the roofing material to locate the fastener a predetermined distance above the edge of the material. This distance is usually limited by the location of the fastening nails 19. It will be apparent from the foregoing that the shingle tabs or shingles require no special design to adapt them for fastening by the aforesaid means, and that when fastened they will lie perfectly flat and will not be buckled or wrinkled in any way. Since the fastening of the free tabs is independent of the sequence of laying the shingles, existing roofs may be fastened down just as easily and satisfactorily as newly laid roofs. In other words the roof may be laid without pre-arrangement as regards the application of the fasteners.

So long as the adequate amount of underlap is provided the area of the shingle may be proportionately very large without resulting in the possibility of leakage, thereby effecting substantial economy in roofing material as well as securing the desired large-shingle effect.

In Fig. 2 is illustrated a roof surface formed by individual square shingles 27 laid in diamond pattern and having the free ends 28 fastened down by the fasteners 20. The shingles 27 are laid diagonally with their upper diagonal margins overlapped (a distance 29 adequate to protect against leakage) by the lower diagonal margins of the overlying course. The lateral corners of the

In Fig. 3 is illustrated a roof covering formed of overlapping courses of shingle strips 35 having a plurality of spaced projecting square-butt tabs 36. The strips are laid with the butts of adjacent courses of tabs 36 in staggered relation. The depth of each strip is made such that the upper edge 37 of each course of strips underlies by a distance 38 the notches or slots 39 between adjacent tabs of the second overlying course. The distance of overlap is usually 2 or 2½" in this type of shingle. It will be apparent that in this roof covering three thicknesses of roofing occur adjacent the bottom of each slot 39. Fastening nails 40 penetrate the lower two thicknesses of material and are concealed and protected by the lower edges of the overlying exposed tabs 36. As here shown the fastening nails are preferably placed close to the bases of the slots or notches 39. The fasteners 20 pass through the upper and next lower thicknesses of the roofing but not the bottom thickness. They may be applied as illustrated in Fig. 1 by an automatic fastener applying device which drives the fastener through the top thicknesses of roofing but not through the bottom thickness. The plate 22 is sufficiently narrow so that the extremity 24 may be passed through a narrow slot 39 and swung underneath the roofing material at the base of the slot where the fastener 20 is to be located. It is obvious from the foregoing that the fasteners 20 may be applied to an old roof or a newly laid roof without any alteration in the conventional design of the roofing material.

In Fig. 4 is shown a roof surfacing comprising rectangular shingles 41 arranged in "Dutch-lap" pattern. Such a pattern is formed by overlapping each course of shingles at their side edges as at 42 by a distance 43 which is conventionally about 2 or 2½". The lower edge of each overlying course overlaps an underlying course by the distance 44 which is conventionally about 2 or 2½". Fastening nails 45 occur at the side overlaps 42 and pass through the lower side lap and also through the upper portion of the next underlying course of shingles. The head of the fastening means is covered by the overlapping side margin 46 of each shingle. The fasteners 20 penetrate

the upper thicknesses of roofing, that is, the overlapping side margins 42 but not the bottom thickness and are preferably located closely adjacent the fastening nails 45. Thus the free overlying corners of each shingle is fastened to the underlying shingle and that in turn is firmly held down by the closely adjacent fastening nail 45.

It is apparent that the shingles may be made of substantial size without increasing the conventional overlap and still be securely held in flat relationship against leakage. No alteration in the conventional design or manner of laying the shingles is required.

Obviously the invention is not limited to details of the illustrative embodiments thereof herein shown and described. These may be variously modified. Moreover it is not indispensable that all of the features be used conjointly, since various features may be employed to advantage in different combinations or subcombinations.

What is claimed is,

1. Roofing of the character described comprising in combination a plurality of overlapping courses of flexible shingle units made of pierceable material and presenting a series of overlapping courses of exposed shingles arranged in spaced relation, said units being of a depth to underlie portions of the second course above thereby providing areas of triple thickness, fastening means passing through the underlying units but not the top unit to attach the same to the roof, said fastening means being covered by a portion of the top unit, and double pronged metal staples located adjacent the lower edge of the uppermost course and closely adjacent said fastening means, the prongs of said staples piercing from above the upper two thicknesses of roofing but not the lower thickness and being upset above the latter, whereby said lower edge of said uppermost course is fastened down without penetration to the roof supporting structure by staples which may be applied after the lower units have been fastened by said fastening means and overlapped by the top course, the section of the wire being sufficient to resist buckling of the staple legs when driven through mineral surfaced roofing.

2. Roofing of the character described comprising in combination a plurality of overlapping courses of flexible shingle units made of pierceable material and presenting a series of overlapping courses of exposed shingles arranged in spaced relation, said units being of a depth to overlie portions of the second course above thereby providing areas of triple thickness, nails or the like passing through the underlying units but not the top unit to attach said underlying units to the roof, said nails being covered by a portion of the top unit, and prong attaching devices located adjacent the lower edge of the uppermost course and closely adjacent said nails, the prongs of said attaching devices piercing from above the two upper thicknesses of roofing but not the lower thickness and being upset above the layer thereby fastening the uppermost course directly to the next underlying course without penetration to the roof supporting structure, said fastening devices being applicable to the roofing after the lower units have been fastened by said nails or the like and overlapped by the top course, the section of the prongs of said fastening devices being sufficient to resist buckling thereof when driven through mineral surfaced roofing.

3. In a roofing assembly of the class described, the combination of a supporting substructure, impregnated felt roofing units overlapping to give three-ply thickness in limited areas and lying flat upon each other in conforming relationship, means securing the lowest of the said units directly to the substructure, and a staple driven through the uppermost unit and the immediate underlying intermediate unit in an area where the thickness is three-ply and near a corner of the uppermost unit, and below the lowest point at which the intermediate unit is secured to the substructure, said staple being clinched above and not passing through the bottom ply.

4. In a structural assembly of the class described the combination of at least three overlapping units of prepared roofing material having exposed tab portions lying flat upon each other in conforming relationship, a supporting substructure therefor, means securing the lowest of the said units directly to the substructure, and a fastening member having an element thereof driven through the exposed tab portion of the uppermost unit, at a position adjacent to a corner thereof, and through the immediately underlying unit and securing the said uppermost and underlying units together, without penetrating the said lowest unit.

5. Roofing of the character described comprising in combination a plurality of overlapping courses of flexible shingle units made of pierceable material and presenting a series of overlapping courses of exposed shingles arranged in spaced relation, said units being of a depth to underlie portions of the second course above thereby providing areas of triple thickness, fastening means passing through the underlying units but not the top unit to attach the same to the roof, said fastening means being covered by a portion of the top unit, and double pronged metal staples located closely adjacent said fastening means, the prongs of said staples piercing from above the upper two thicknesses of roofing but not the lower thickness and being upset above the latter, whereby said lower edge of said uppermost course is fastened down without penetration to the roof supporting structure by staples which may be applied after the lower units have been fastened by said fastening means and overlapped by the top course.

6. Roofing of the character described comprising in combination a plurality of overlapping courses of flexible shingle units made of pierceable material and presenting a series of overlapping courses of exposed shingles arranged in spaced relation, said units being of a depth to overlie portions of the second course above thereby providing areas of triple thickness, fastening means passing through the underlying units but not the top unit to attach said underlying units to the roof, said fastening means being covered by a portion of the top unit, and pronged attaching devices located closely adjacent said fastening means, the prongs of said attaching devices piercing from above the two upper thicknesses of roofing but not the lower thickness and being upset above the layer thereby fastening the uppermost course directly to the next underlying course without penetration to the roof supporting structure, said fastening devices being applicable to the roofing after the lower units have been fastened by said fastening means and overlapped by the top course.

HARRY L. GUY.
